DEVICE FOR FORMING SELVAGES ON
WOVEN FABRICS

Albert Moessinger, Winterthur, Switzerland, assignor to Sulzer Frères, Société Anonyme, Winterthur, Switzerland

Application August 11, 1942, Serial No. 454,399
In Switzerland September 19, 1941

8 Claims. (Cl. 139—54)

Looms are known in which the outermost warp threads are specially manipulated by means of a continuously rotating device. These warp threads are unwound from two bobbins mounted in a rotating bobbin carrier.

When starting the loom, all these devices give very neat selvages, but the edges gradually become worse until the edgebinding threads finally break. The drawback of such devices consists in that the bobbins mounted in the bobbin carrier make a complete rotation about themselves for each rotation of the bobbin carrier. The binding threads unwound from the rotating bobbin carrier therefore receive, for each second pick, one turn more or one turn less between the fabric and the bobbins. After several thousand picks the binding threads have a very great change in twist which cannot be compensated by the comparatively small forward motion of the binding threads, so that the strands of these threads become quite untwisted or so strongly twisted that they break.

The invention eliminates this drawback in that at least one of the two warp threads operating as binding threads is unwound from a bobbin mounted in a continuously rotating bobbin carrier. The invention consists in that the bobbin makes with respect to the bobbin carrier also a motion influencing the twist of the binding thread. With advantage the two warp edge threads operating as binding threads can be unwound from two separate bobbins mounted in the continuously rotating bobbin carrier, the two bobbins making with respect to the bobbin carrier also a motion influencing the twist of the binding threads. The average angular rotation of the bobbin, with respect to the bobbin carrier and affecting the twist of the thread, can be as great as the average angular rotation of the bobbin carrier. The angular speed of the motion of the bobbin with respect to the bobbin carrier and affecting the twist of the thread can be as great as the angular speed of the bobbin carrier. Preferably the axis of rotation of the motion of the bobbin affecting the twist of the thread is parallel to the axis of rotation of the bobbin carrier, so that the bobbin makes a movement of translation.

One of the two binding threads can be drawn through the hollow shaft of the bobbin carrier from a bobbin rotating round a stationary axle. A rotating disk, revolving always in the same direction and causing the binding of the binding threads, can be mounted between the rotating bobbin carrier and the fabric. The axis of rota-

tion of this disk can lie approximately in the plane of the warp at right angles to the warp threads, so that the disk takes up as little room as possible between the warp threads. The disk may also be fitted with an outer toothed annulus and be driven and guided by two positively-operated toothed wheels. It can, however, also be driven and guided by one positively-operated and two free-running toothed wheels. By means of a Geneva-gear mechanism the disk may be caused to rotate intermittently and the bobbin carrier can continually rotate at the same mean angular speed. Easily changeable operating pins may be provided on the driver of the Geneva-gear mechanism for changing the binding of the binding threads.

Between the bobbin carrier and the rotating disk a warp thread stop motion can be mounted, in which the two binding threads are passed through the same plate spring of the stop motion and each binding thread is brought by the rotation of the bobbin carrier or of the disk alternately into such a position that it raises the plate spring of the stop motion, whilst the other binding thread has no influence on the plate spring. Immediately after the bobbin a thread brake moving with the axis of the bobbin, may be mounted on the bobbin carrier.

Some examples of execution according to the invention are shown diagrammatically in the drawings.

Fig. 1 is a longitudinal section and
Fig. 2 a view from above of the device according to the invention.

Fig. 3 is a section through the bobbin carrier, in which the drive of the motion of the bobbin can be seen.

Fig. 4 shows in section a modification for supporting the bearing of the rotating disk,

Fig. 5 the same in side view.

Fig. 6 shows a section and

Fig. 7 a side view through the drive of the rotating disk by means of a Geneva-gear.

Fig. 8 shows a modification of the bobbin carrier illustrated in Fig. 1.

According to Fig. 1 the warp threads 1 run from the warp beam 2 over the back rail 3 through the warp stop motion 4, the heddles 5, and the reed 6 to the fabric 7, which is wound onto the cloth beam 8. The binding threads 9 and 10 run separately from the bobbins 11 and 12 through the thread brakes 13 and 14 and through the eyes 15 and 16. From here the two binding threads 9 and 10 run together in a vertical slit 17, through a spring plate 18 of the stop

motion 4 and through the eye 19. Then the two binding threads 9 and 10 run again separately through the two guide eyes 20 and 21 of the rotating disk 22 and finally together through the reed 6 to the fabric 1.

The two bobbins 11 and 12 are mounted in one common bobbin carrier support 23, which is subjected by the helically toothed wheels 24 and 25 to a rotation which may be continuous. When the binding threads 9 and 10 are drawn from the bobbin, the bobbins 11 and 12 rotate on their axles 26 and 27 and receive a light braking action from the springs 30. The axles 26 and 27 are fixed in stirrups or carriers 28 and 29, which are pivotably mounted on the bobbin carrier 23 and rotate round the axles 31 and 32, these axles being at right angles to the axles 26 and 27.

The bobbin carrier 23 is pivotably supported on a pin 33 rigidly connected to the support 34. This pin 33 is connected to a toothed wheel 35 (Figs. 1 and 3). The axles 31 and 32 are also fitted with toothed wheels 36 and 37 which mesh with the toothed wheel 35 by means of toothed wheels 38 and 39. For each rotation of the bobbin carrier 23, the axles 31 and 32 will carry out a movement through the meshing of the toothed wheels 35-39.

In this way the binding threads 9 and 10 do not change their twist during the running of the loom. The support 34 is rigidly held by a tube 40 rigidly connected to the loom. On the support 34 the driving shaft 41 of the toothed wheel 25 is carried. In Fig. 1 the disk 22 is rotated and also guided by two toothed wheels 42 driven by the shafts 43 and 44. These shafts 43 and 44 are carried in a frame 45 rigidly connected to the loom. The toothed wheels 42 are also provided with disks 46 which make it possible to guide the rotating disk 22 laterally.

The two binding threads 9 and 10 are passed through the same spring plate 18. In order that the stop motion may be influenced by both these threads, the two threads are alternately moved up and down by the motion of the bobbin carrier 23. When the thread 9 is brought to the top it raises the plate spring 18. On the other hand the lower binding thread 10 is so far down that the plate spring 18 is no longer raised by it if the upper thread 9 breaks, and the loom is stopped by a known device, for instance by closing the electric contact between the rails 70 and 71.

The rotating disk 22 and the bobbin carrier 23 are, for the sake of clearness, drawn in such a position that the run of the two binding threads is visible over their whole length. Preferably, however, the plane formed by the two binding threads between the bobbin carrier and the warp stop motion 4, and the plane between the warp stop motion and the fabric, are displaced with respect to each other by 90°, so that a compensation of the tension of the binding threads takes place when the shed is open or closed.

In Figs. 4 and 5 a modification of the position of the rotating disk is given. The rotating disk 22 is operated by a toothed wheel 42 driven by the shaft 43 and is guided by the two toothed wheels 47 freely carried in the frame 48 which is rigidly connected to the loom. The lateral guiding of the disk 22 is ensured on the one hand by the lateral disks 46 connected to the toothed wheel 42, and on the other hand by the plates 49 connected to the fixed frame 48.

In Figs. 6 and 7 the drive of the rotary disk by means of a Geneva gear mechanism is shown. The sprocket 50 driven by the loom is fixed to the

operating hub 51, which is rotatably supported on the axle 53 fixed on the support 52. The support 52 is rigidly connected to the loom. The hub 51 carries a disk 51' on which the operating pins 54 are fixed. On this disk 51' a safety member 55 is also provided; it meshes in the arcuate outer part of the Geneva gear 56 and secures the Geneva gear in its position.

The Geneva gear 56 is rigidly keyed on the shaft 57 which is rotatably carried on the support 52. This shaft 57 drives also a toothed wheel 58 which operates the driving shafts 43 and 44 of the rotary disk 22 by means of the toothed wheels 59. The sprocket wheel 50, driven by the loom, drives through a chain 60 the shaft 41 which transmits the rotary motion of the bobbin carrier.

The difference between the arrangements illustrated in Fig. 8 and in Fig. 1 consists in the axis of rotation 72 (31 in Fig. 1) of the motion of the bobbin 73 (11 in Fig. 1), which causes the rotation of the thread 9, being arranged at right angles to the axis of rotation 74 of the bobbin carrier 75 (23 in Fig. 1) and the bobbin carrier support 75 containing only one bobbin 73. The second thread 10 is guided through an eye 76 which moves with the bobbin carrier support 75. This thread 10 is afterwards led through the hole 77 in the shaft round which the bobbin carrier 75 rotates and comes either from a bobbin which is carried on a pin rigidly connected to the loom, or from the warp direct. The motion influencing the twist of the thread is transmitted through the bevel wheel 79, which is rigidly connected to the stationary part 78, by means of the planet bevel wheel 80 to the bevel wheel 82 connected to the stirrup or bobbin carrier 81. The bobbin carrier 75 is driven through the toothed wheels 83 and 84 by the driving shaft 85.

I claim:

- 40 1. A mechanism for forming selvages on fabrics woven on gripper shuttle looms, comprising, in combination, a device supplying the edge forming warp threads and comprising a bobbin from which a warp thread is unwound, a disc-like warp thread guide member rotating about an axis substantially parallel to the weft threads and receiving the edge forming warp threads from said supply device and twisting same together between said disc-like member and the fabric, said edge forming warp threads moving from said supply device, and the latter rotating in such direction and at such speed relatively to the direction and speed of rotation of said disc-like guide member as to prevent twisting of said edge forming warp threads between said device and said guide member, and a drive mechanism for said guide member comprising a rotating member having stud members extending therefrom parallel to the axis of its rotation, a Geneva gear having slot means periodically engaged by said stud members, and other gear means connected with said Geneva gear and engaging the periphery of and, due to the action of said Geneva gear, periodically rotating said disc-like member.
- 45 2. A mechanism for forming selvages on fabrics woven on gripper shuttle looms, comprising, in combination, a device supplying the edge forming warp threads and comprising a bobbin from which a warp thread is unwound, a disc-like warp thread guide member rotating about an axis substantially parallel to the weft threads and receiving the edge forming warp threads from said supply device and twisting same together between said disc-like member and the fabric, said edge forming warp threads moving from said
- 50 3. A mechanism for forming selvages on fabrics woven on gripper shuttle looms, comprising, in combination, a device supplying the edge forming warp threads and comprising a bobbin from which a warp thread is unwound, a disc-like warp thread guide member rotating about an axis substantially parallel to the weft threads and receiving the edge forming warp threads from said supply device and twisting same together between said disc-like member and the fabric, said edge forming warp threads moving from said
- 55 4. A mechanism for forming selvages on fabrics woven on gripper shuttle looms, comprising, in combination, a device supplying the edge forming warp threads and comprising a bobbin from which a warp thread is unwound, a disc-like warp thread guide member rotating about an axis substantially parallel to the weft threads and receiving the edge forming warp threads from said supply device and twisting same together between said disc-like member and the fabric, said edge forming warp threads moving from said
- 60 5. A mechanism for forming selvages on fabrics woven on gripper shuttle looms, comprising, in combination, a device supplying the edge forming warp threads and comprising a bobbin from which a warp thread is unwound, a disc-like warp thread guide member rotating about an axis substantially parallel to the weft threads and receiving the edge forming warp threads from said supply device and twisting same together between said disc-like member and the fabric, said edge forming warp threads moving from said
- 65 6. A mechanism for forming selvages on fabrics woven on gripper shuttle looms, comprising, in combination, a device supplying the edge forming warp threads and comprising a bobbin from which a warp thread is unwound, a disc-like warp thread guide member rotating about an axis substantially parallel to the weft threads and receiving the edge forming warp threads from said supply device and twisting same together between said disc-like member and the fabric, said edge forming warp threads moving from said
- 70 7. A mechanism for forming selvages on fabrics woven on gripper shuttle looms, comprising, in combination, a device supplying the edge forming warp threads and comprising a bobbin from which a warp thread is unwound, a disc-like warp thread guide member rotating about an axis substantially parallel to the weft threads and receiving the edge forming warp threads from said supply device and twisting same together between said disc-like member and the fabric, said edge forming warp threads moving from said

supply device, and the latter rotating in such direction and at such speed relatively to the direction and speed of rotation of said disc-like guide member as to prevent twisting of said edge forming warp threads between said device and said guide member, and a drive mechanism for said guide member comprising a rotating member having stud members extending therefrom parallel to the axis of its rotation, a Geneva gear having slot means periodically engaged by said stud members, and other gear means connected with said Geneva gear and engaging the periphery of and, due to the action of said Geneva gear, periodically rotating said disc-like member, a safety guide member connected with said rotating member and having an arcuate peripheral portion, and said Geneva gear having arcuate peripheral portions periodically engaging and meshing with the arcuate peripheral portion of said safety guide member.

3. A mechanism as set forth in claim 1 said stud members being removably connected with said rotating member.

4. A mechanism for forming selvages on fabrics woven on gripper shuttle looms, comprising, in combination, a supply device supplying the edge forming warp threads and comprising a bobbin from which a warp thread is unwound, and a disc-like warp thread guide member rotating about an axis substantially parallel to the weft threads and receiving the edge forming warp threads from said supply device and twisting same together between said disc-like member and the fabric, said edge forming warp threads moving from said supply device, and the latter rotating in such direction and at such speed relatively to the direction and speed of rotation of said disc-like guide member as to prevent twisting of said edge forming warp threads between said device and said guide member, said supply device including a bobbin carrier carrying said bobbin and rotating about an axis which is substantially in the direction of the edge forming warp thread running off said bobbin and from said device.

5. A mechanism for forming selvages on fabrics woven on gripper shuttle looms, comprising, in combination, a supply device supplying the edge forming warp threads and comprising a bobbin from which a warp thread is unwound, and a disc-like warp thread guide member rotating about an axis substantially parallel to the weft threads and receiving the edge forming warp threads from said supply device and twisting same together between said disc-like member and the fabric, said edge forming warp threads moving from said supply device, and the latter rotating in such direction and at such speed relatively to the direction and speed of rotation of said disc-like guide member as to prevent twisting of said edge forming warp threads between said device and said guide member, said supply device including warp thread brake means interposed and braking the movement of the edge forming warp thread between said bobbin and said guide member.

6. A mechanism for forming selvages on fabrics woven on gripper shuttle looms, comprising,

5 in combination, a supply device supplying the edge forming warp threads and comprising a bobbin from which a warp thread is unwound, and a disc-like warp thread guide member rotating about an axis substantially parallel to the weft threads and receiving the edge forming warp threads from said supply device and twisting same together between said disc-like member and the fabric, said edge forming warp threads moving from said supply device, and the latter rotating in such direction and at such speed relatively to the direction and speed of rotation of said disc-like guide member as to prevent twisting of said edge forming warp threads between said device and said guide member, said supply device including a rotating bobbin carrier rotatably carrying said bobbin, brake means associated with and braking the speed of rotation of said bobbin, and warp thread brake means 10 mounted on said carrier along the path of said warp thread and braking the motion thereof after leaving the bobbin.
